Primary Examiner—Raphael Barkai*Assistant Examiner*—Randall H Gholson(74) *Attorney, Agent, or Firm*—Tsircou Law, P.C.(57) **CLAIM**

We claim the ornamental design for an ergonomic wrench, as shown and described.

DESCRIPTION

FIG. 1 is a left side perspective view of an ergonomic wrench in accordance with the new design.

FIG. 2 is a front elevational view of the ergonomic wrench of FIG. 1, with the movable jaw closed.

FIG. 3 is a back elevational view of the ergonomic wrench of FIG. 2.

FIG. 4 is a left side elevational view of the ergonomic wrench of FIG. 2.

FIG. 5 is a right side elevational view of the ergonomic wrench of FIG. 2.

FIG. 6 is a top view of the ergonomic wrench of FIG. 2; and, FIG. 7 is a bottom view of the ergonomic wrench of FIG. 2. The dashed lines depict environmental aspects and form no part of the claimed design.
